UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

SUPERHEAT-LIMITING DEVICE.

1,328,997.

Specification of Letters Patent. Patented Jan. 27, 1920.

Application filed December 14, 1916. Serial No. 136,832.

To all whom it may concern:

Be it known that I, DAVID S. JACOBUS, a citizen of the United States, residing in Jersey City, in the county of Hudson and

5 State of New Jersey, have invented certain new and useful Improvements in Superheat-Limiting Devices, of which the following is a specification.

My invention relates to an apparatus for 10 limiting the maximum amount of superheat in superheated steam, and will be understood by reference to the accompanying drawings in which Figure 1^A is a diagrammatic view to illustrate the principle of operation of my invention; Fig. 1, a side view of an independently fired superheater having the superheat limiting device applied thereto; Fig. 2, a side view partly in section, of one of the doors for admitting air into 15 the setting, with the lever for opening same; Fig. 3, a front view of one of the doors; Fig. 4, a front view of Fig. 1; Fig. 5, a vertical longitudinal section through the superheater; Fig. 6, a side view of the 20 connections for passing the steam from one section to the other of the superheater; Fig. 7, a vertical longitudinal section, with certain parts in elevation, of a series boiler to which the device is applied; Fig. 8, is a side 25 view, with certain parts in section, of a part of the apparatus for effecting the regulation shown on a smaller scale in Figs. 1 and 7; Figs. 9 and 10 are enlarged views, partly in section, of parts of the valve and 30 stem of Fig. 8; Fig. 11 is a side view, partly in section, of a modified form of the apparatus for effecting the regulation; Fig. 12 is a top view of Fig. 11; Figs. 13, 14 and 35 15 are enlarged views of the operative mechanism and diaphragm of the apparatus shown in Fig. 11; Fig. 16 is a side view, mainly in section, showing a balanced valve which may be used in connection with the apparatus, the valve being shown closed; 40 Fig. 17 is a view similar to Fig. 16, showing the valve open; Fig. 18 is a transverse section on the plane of the line 18—18 of Fig. 17; Fig. 19 is a transverse section on the plane of the line 19—19 of Fig. 17; Fig. 20 is a 45 transverse section on the plane of the line 20—20 of Fig. 17; Fig. 21 is a side view, mainly in section, of another form of valve which may be employed for operating the power piston; Fig. 22 shows the same valve 50 in open position; and Fig. 23 is a side view, 55

mainly in section, of a further modification of the apparatus for effecting the regulation. Similar reference numerals indicate similar parts in the several views.

In the adaptations, hereinafter described, 60 of my invention to superheater practice, I employ a thermostat placed in the path of the outgoing superheated steam. In the form shown this comprises a container for a volatile liquid, the temperature of such 65 liquid, and consequently the pressure of its vapor, varying as the temperature of the surrounding superheated steam varies. This vapor pressure generated in the container is utilized to set in operation certain mechanisms to limit the temperature within the 70 superheater setting and thus limit the degree of superheat. For the purpose of explaining the principle of operation of my invention, I have shown a diagrammatic 75 arrangement in Fig. 1^A in which the numeral 1 designates a portion of the superheated steam main. Within this main is a container in the form of a coiled pipe 2 closed to the steam and containing a volatile liquid such 80 as water, alcohol or mercury having a fixed boiling point for a given pressure. The container may have any appropriate form which will insure an effective impingement of the superheated steam and a relatively 85 large heating surface with the proper internal volume. The upper end of the coil 2 is secured in an opening in the cap 3 closing the end of the steam main, said cap having a chamber 4 from which a pipe 5 90 leads to a regulator. The coil 2 is only partially filled with liquid, the space above the liquid being filled with vapor, the pressure of which corresponds to the temperature to which the liquid is heated by the 95 superheated steam. The latter regulator comprises a chamber 6 having a flexible diaphragm 7 upon which diaphragm rests a disk 8. When water is used as the liquid in the coiled pipe 2 the chamber 6 is filled 100 with water upon the surface of which oil is placed to prevent corrosion of the diaphragm 7, which is preferably of hardened steel. For a given steam temperature passing over the coil 2 there will be a given 105 vapor pressure transmitted to the chamber 6. This pressure acting upon the under side of the diaphragm 7 is transmitted through the following mechanism:—

The post which bears on the disk 8 is 110

pivoted to a lever 9 having its fulcrum at 10. To the free end of the lever 9 is attached the stem of a valve 11 which valve controls the flow of a fluid under pressure, preferably water, entering through pipe 12 from a source of supply. From the valve chamber the fluid under pressure is delivered through a pipe 13 to a cylinder 14 having a piston 15, which latter is connected to a power lever 16 having its fulcrum at 16'. To the end of lever 16 is attached a rod 17, the movements of which rod are utilized as hereinafter described. When the valve 11 is closed, by a reduction of the vapor pressure on diaphragm 7, the power lever 16 is restored to its normal position by a counterweight 16², the water in the cylinder being discharged through a valved pipe 18. The valve in the pipe 18 is partially open at all times and the valve is not changed in position when the mechanism is in operation. The valve in the pipe 18 is so adjusted that during the time the water is being admitted to the cylinder 14, through the pipe 13, the discharge through the pipe 18 is materially less than the rate at which the water is admitted through pipe 13. The upward movement of lever 9 is opposed by a spring 9' and is limited by a stop 9².

30 The action of the regulator above described is to cause the vapor pressure generated in coil 2 to act through the regulator in such manner that when the temperature of the superheated steam flowing through the main 1 exceeds that for which the apparatus is set, the lever 9 will be raised to thereby open valve 11 to admit water under pressure to the working side of piston 15. When the piston 15 is moved, the power lever 16 will be moved and thereby the rod 17, to effect a reduction in the temperature of the superheated steam as will be more fully described in connection with Figs. 1 to 7. When the temperature of the steam 45 is reduced below that at which the apparatus is set, the valve 11 will be moved to its seat by the spring 9'.

On closing the valve 11 the water discharged through the valve in the pipe 18 50 will allow the power piston 15 to slowly regain its original position near the top of the power cylinder 14, the lever 16 having a counterweight 16² which moves the power piston 15 to its original position. In place 55 of the counterweight 16² the system may be otherwise counterweighed, in which case it may not be necessary to use a counterweight on the lever 16.

The advantage of allowing the water 60 which operates the power piston 15 to escape at all times through a constricted opening is that it provides a simple means whereby the power piston 15 may return to its original position after the mechanism has 65 been thrown into action, and further, there

are special advantages in using this method as the apparatus may be operated through a very small movement of the valve 11. The method described is superior in these respects to one where the water is released 70 from the power cylinder by means of a valve actuated by the same mechanism that actuates the valve 11, as the latter arrangement would require a much closer adjustment and would be much more liable to get out 75 of order than the one described.

In Figs. 1 to 5 inclusive, I have shown an adaptation of my invention to an independently fired superheater in which, when the maximum degree of superheat is reached, 80 doors will be opened to admit atmospheric air into the setting to thereby reduce the steam temperature. The superheater illustrated is substantially the same as that described in my application Serial No. 45,399, 85 filed August 13, 1915. As shown in Fig. 5, the steam from the boiler enters through the main 19, thence passes into the superheater header 20, through the tubes 21 into the header 20'. From the latter the steam 90 flows through pipe 22, which is placed outside of the setting, into the superheater header 23, through the tubes 24 to header 23'; thence through pipe 25, which is outside of the setting, into the header 26, 95 through tubes 27 to header 26'; thence through pipe 28 to header 29, through tubes 30 to outlet header 29'; and thence to the steam main 1. The gases from furnace 31 flow into the secondary combustion chamber 31' and thence successively over the banks of tubes 21, 30, 27 and 24 to the damper opening 32. It will be noted that the saturated steam which is admitted to the superheater, passes through the bank of 100 tubes 21 which is acted on by the hottest gases, thus minimizing the tendency of the hot gases to burn and distort the tubes which come nearest the fire. Also that the steam is so circulated through the remaining banks 105 of tubes that the hottest steam comes in contact with the hottest gases and the coldest steam comes in contact with the coldest gases, the counter flow principle thus being made use of for all banks except the one 110 nearest the fire. This arrangement leads to the maximum transfer of heat and when combined with the feature of maintaining the bank which comes nearest the fire at a low enough temperature to prevent trouble, 115 through burning of tubes, a superheater is provided having a high efficiency coupled with the practical advantage of requiring a 120 minimum expense for upkeep.

The superheater is fired by any suitable 125 furnace, the fire in which is so regulated as to maintain the desired degree of superheat. Should, however, the superheat exceed the desired maximum, atmospheric air is admitted to the interior of the setting to 130

reduce the temperature to a point below the maximum. In the construction shown the front wall of the setting is provided with doors 33 adapted to be opened and closed by the power lever 16 and rod 17, shown in Figs. 1 to 5 as follows:—

The rod 17 is attached at its upper end to a lever 34 on a rock shaft 35. To the latter are secured levers 36 which, when the 10 shaft is rotated, engage rollers 37 mounted on the doors to open the latter to admit atmospheric air into the setting. Also attached to the shaft 35 is a lever 38 carrying a counterweight 38' set at such an angle 15 with respect to the shaft 35 that it will be inactive in producing a force tending to open the doors when the latter are closed. In order to properly adjust the action of the counterweight 38', a second counterweight 39' is carried by a lever 39, also secured to shaft 35. The action of the power lever 16 in completely releasing the doors, when in a closed position, is an important one as it allows the doors to rest firmly 20 against their seats when closed, and so minimize air leakage. The doors are made to seal tightly against their frames by the use of asbestos or other packing. Any number of doors may be provided. In Fig. 4, I 25 have shown 5 doors arranged in two rows, those on the lower level being actuated by a shaft 40 connected to shaft 35 by a link 41 and lever 42. To open the doors the shaft 35 is given a clockwise motion causing levers 36 to engage with the rollers 37, and on further rotating the shaft 35 in the same direction, the doors will be opened until they assume the position indicated at the top of Fig. 2. When the temperature 30 of the superheated steam falls, the counterweights 38' and 39' act to raise the lever 16 to its normal position, said counterweights being so set that, together with the unbalanced weight of the doors, there will be an 35 upward force produced on the rod 17.

The pressure gage 43, shown in Fig. 1, is acted on by the pressure transmitted from the coil 2 through the tube 5. This gage has been found of great assistance in the 40 operation of the superheater as it is highly sensitive in indicating changes in temperature in the superheated steam, as changes in the pressure of the vapor in coil 2 depend upon changes in the temperature of 45 the superheated steam. I also show at 44 a recording thermometer, the hot end of which is at 44' within the main 1. The thermometer 44 is included in an electric circuit which circuit also includes a bell 45 adapted to be rung when the superheated steam reaches a set figure, thus giving an alarm to warn the fireman. The current for operating the bell is supplied from the batteries 45'. The use of the recording 50 thermometer and the alarm bell is, of course,

supplemental to the use of the superheat limiting device.

The apparatus above described is set to operate at a temperature somewhat higher than the average amount of superheat given 70 by the superheater and should the superheat either accidentally or by design attain the temperature to which the device is set, the latter will act to prevent a further increase of superheat. In the actual use of 75 the device it has been found that by proper hand manipulation of the fires it is seldom called upon to act, but its use is, nevertheless, highly essential as it provides a safeguard against an excessive amount of superheat which might cause trouble in the power system. Such a device would be wasteful if applied as a regulator to be continually in action to maintain a given degree of superheat, but when used as an 80 emergency device for limiting the maximum amount of superheat the loss in efficiency by admitting cold air into the setting does not militate against it. The limiting device is especially applicable to independently fired superheaters, as they are subjected to severe conditions when there is a sudden diminution in the rate at which steam is drawn through them or when there is a sudden stoppage in the flow of 85 steam. To make the described device operative there must be some steam flowing through the main 1. This is accomplished in practice by arranging the power units so that there is little possibility of all of 90 them being shut down at once. In cases where the main units take all of the steam a connection will be provided whereby should it be necessary to suddenly shut down the units, a certain amount of steam 95 will be discharged to waste, thus insuring that some steam will flow through the superheater.

In Fig. 7, I have shown my invention applied to a series boiler in which the feed 100 water is delivered through a valved pipe 46 to the header 47. From this header the water flows through tubes 48 into header 49, and from the latter the water and any contained steam flows from one header to the next through the tubes of the series, and finally all of the water is evaporated and the steam on passing through the remaining tubes of the series is superheated and leaves 105 the boiler through the steam main 1. In addition to the doors 33 for admitting air at the front of the setting, I may place doors 33' for admitting air at the side of the setting and another, 33'', for admitting air at the rear of the furnace. In this arrangement, the rod 17 is connected through a chain to a drum 51 from which a chain 52 leads to an arm on the shaft 35, the rotation of said shaft opening the front doors 33. A second chain 52', from drum 51, is con- 110 115 120 125 130

5 nected to a damper 53 in the blast flue leading to the stoker air-box 54. A third chain 52², from drum 51, is connected to the flue damper 55, the parts being so adjusted that
10 5 the damper 55 will be moved to full open position when the damper 53 is partially closed. A fourth chain 52³, from drum 51, is connected to a lever for operating the door 33². In the drawing the doors are shown open with lever 16 in its lowermost position. When lever 16 is raised the doors 33, 33' and 33² will close and damper 53 will be moved to its full open position indicated by dotted lines.

15 15 In the operation of the series boiler the limiting device will be set to operate at the desired maximum temperature of the superheated steam, the device acting only in the case of an emergency to prevent a degree of 20 superheat above the maximum. To maintain the superheat under normal working conditions at a substantially set figure, the fires and the amount of water admitted to the boiler will be properly regulated. This 25 regulation may be by hand or by a controlling device governed by the pressure generated in coil 2.

30 The series boiler shown may act as an economizer as well as a boiler and in this way combine an economizer, boiler and superheater. It may, however, be fitted with any other form of economizer through which the waste gases will be passed, and in most cases to an induced draft fan. Under conditions where an induced draft fan is employed, the superheat limiting device may be so arranged as to regulate the speed of the fan and thus limit the volume of cold air entering the setting.

35 40 It will be understood that by the expression "superheater", as used herein, I mean to include any arrangement for generating or heating steam or gases whose temperature it is desired to regulate or control, such 45 for example as the series boiler illustrated in Fig. 7, as well as the usual type of superheater, in which the superheater tubes are separate from the boiler tubes.

50 55 In Figs. 8, 9 and 10, I have shown, on an enlarged scale, the mechanism illustrated in Figs. 1 and 7 for operating the power lever 16, this mechanism embodying certain features of construction differing from that shown in the diagrammatic Fig. 1^A. Water has been used as the evaporating agent in coil 2, in the practical use of the device, herein described. After the apparatus has been installed water is pumped into the coil 2 through a valved pipe 58 having a removable plug in its end, as shown. This filling takes place with steam flowing through the main 1 and when the water has been heated it is blown out through the open end of pipe 58 and the apparatus then re-filled. 60 65 By repeating this operation several times all

70 the air is driven out of the apparatus and when it is finally filled the surplus water is allowed to drip slowly from the pipe 58 until the pressure indicated by the gage 43 corresponds to the temperature of the coil 2. This point can be readily determined as the pressure falls quickly on first allowing the water to drip from pipe 58, whereas the moment the pressure corresponding to the temperature of the coil 2 is reached, there is 75 no further fall in pressure. When the apparatus is set up and in operation the discharge outlet of the valve at the end of the pipe 58 is closed by the plug. The diaphragm chamber 59 must be filled with oil, or with water and oil, before the coil 2 is filled.

80 85 The chamber 59, as shown, is formed with a projection 59' to limit the downward movement of the diaphragm 60. Resting upon the diaphragm is a strut or post 61 which bears against a knife edge 62 carried by lever 63. The tension of spring 9' may be adjusted by a nut 9² to hold the lever 63 firmly against the stop 9⁴, and to provide 90 the requisite resistance to the upward movement of the strut 61. To the end of the lever 63 is attached the spindle 64' of a valve 64 shown on an enlarged scale in Fig. 9. Said valve is formed so that it will 95 take its position firmly on the seat 64². Both the seat 64² and the valve bonnet 64³ may be readily taken out and replaced. When the valve is opened by the pressure generated in coil 2, acting through diaphragm 100 60, strut 61 and lever 63, water under pressure will be admitted through supply pipe 12 to cylinder 14, thereby moving piston 15, connected power lever 16 and rod 17 to effect the opening of doors as before described. As shown in Fig. 10, a spring 65 is interposed between the end of lever 63 and a supporting piece carried by the valve spindle 64'. When valve 64 is closed, the lever 63 and spring 65 are in the positions 110 shown in Fig. 10, so that a certain amount of play will be allowed between the lever and a piece 65' carried by the spindle, and having an enlarged head above the end of the lever. The initial upward movement 115 of lever 63 takes up the lost motion and the continued movement of the lever will bring it against the piece 65' to open the valve.

120 125 The valve casing is formed with a passage 66 leading from the upper end of cylinder 14 to the discharge pipe 18. A portion of the water entering through pipe 12 is permitted to escape through the passage 66, the amount being regulated by a valve at the end of the threaded piece 66'. The amount of water so escaping is much less than that which flows inward through the valve 64 so that the piston 15 will be forced downward irrespective of the fact that some 130

of the water escapes through the passage 66. The leakage water which passes upward around the lower part of the valve spindle 64' escapes through a passage 67 into the waste pipe 18. When the temperature of the steam flowing through the main 5 falls to a point which reduces the pressure in coil 2 sufficient to allow valve 64 to be closed by spring 9', the counterweight 10 16² attached to lever 16, will return the piston 15 to its normal position, the water in the cylinder escaping through passage 66 and pipe 18. Fig. 11 shows certain modifications of the apparatus of Fig. 8. This 15 form employs a knife edge 68 and shackle 69 for transmitting the force from spring 9' to lever 63. The connection between the end of lever 63 and the valve spindle 64' has been modified by attaching a piece 70 20 to the end of the lever by a screw, as shown. Also in this form the threaded piece 66' for throttling the water flowing through passage 66, is carried by a sleeve 66².

The diaphragm and its casing have also 25 been changed as indicated, that is, the member 71 in which the strut 61 is supported, is held by bolts 71', and in common with the first form described is of substantial construction in order to provide the rigidity 30 and strength necessary for forming and maintaining a good joint at the edges of diaphragm 72. As shown, in the enlarged view Fig. 15, the member 71 is formed with a projection 71² and the diaphragm is firmly 35 held between said projection and a corresponding depression in the base member 73. The lower end of strut 61 is seated in a cap 61' which fits into the central depression of diaphragm 72. The diaphragm has only 40 a slight upward movement which is allowed for by providing a clearance as indicated at 72', the form of the diaphragm being of importance in the construction and operation of the apparatus. The amount that 45 the cap 61' and strut 61 can rise is limited by allowing the proper clearance above the top of the cap and the face 71³ of member 71. A certain amount of clearance is left between the top of the projecting stop 59' 50 and the lower part of the diaphragm, this clearance being so regulated that should the strut 61 be forced downward to bring the diaphragm firmly against the stop, there will be no injury to the diaphragm.

55 Figs. 16 to 20 show a balanced valve for admitting water to the power piston, said valve comprising two members 74 and 75 screwed together as indicated and having, respectively, two faces 74' and 75' of the 60 same form and dimensions. These valve faces seat against corresponding stationary faces 76 and 77. The member 78, on which is formed the seat 76, is removably held by a pin 78' passed through its lower end. 65 By making the valve face 74' and its seat

76 of the same form and size as the face 75' and its seat 77, the valve will be balanced and will require but little force to open and close it as compared with an unbalanced valve having the same capacity 70 for the flow of water.

Figs. 21 and 22 illustrate a further modification in the valve for admitting water to the power cylinder and the means for operating it. In this form the valve 79 and 75 its hollow stem 79' are preferably made in one piece. The valve casing is formed with a passage 12' leading from the pipe 12 which is connected to a source of water under pressure, said passage opening into a 80 space in the casing below the valve so that an upward pressure will be exerted by the water on the valve. In the lower part of the valve body are two ducts 80 through which water is permitted to flow into the casing 85 above the valve. In the valve stem 79' are two sets of ducts 81 and 82, the latter being normally closed, as shown in Fig. 21, by a spindle 83 connected to the end of lever 63, said lever being actuated by pressure generated in the coil 2 in the superheated steam main 1, as hereinbefore described. The spindle 83 passes through the valve stem 79' to near the lower end thereof, to provide a chamber 84. The ducts 81 afford communication between the space above the valve 79 and the chamber 84, and the ducts 82 afford communication, when open as shown in Fig. 22, between said chamber and a chamber 85 opening into a passage 100 85' which latter discharges into the waste pipe 18 through a nipple 85². When the spindle 83 is in its lowermost position so that it covers the ducts 82, the water pressure below and above the valve is equalized 105 as the water is permitted to enter the space above the valve through the ducts 80 and into the chamber 84 through the ducts 81, but cannot escape through the ducts 82. When the spindle 83 is raised by lever 63, 110 the ducts 82 will be uncovered, allowing the water above the valve to discharge to the waste pipe 18 and thus relieve the pressure above the valve. When this occurs, the water pressure below the valve will open it, 115 allowing the water from pipe 12 to enter the power cylinder 14, the valve in its opening movement causing its stem 79' to slide along the spindle 83. Surrounding the lower end of the valve stem is a spring 86 between the 120 valve and a cap 87 screwed into the casing, said spring being compressed when the valve is raised. When the superheat is lowered to an extent which will cause the lever 63 to fall, spindle 83 will be moved downward thus closing the ducts 82 and allowing the water pressure to build up in the space 125 above the valve. When the pressure is equalized, the spring 86 will close the valve.

In Fig. 21 the power piston is shown as 130

returning to its normal position after the valve 79 has been closed, the water above the piston during this time escaping through the passage 66 and thence to the waste pipe 18. A drain 14' near the bottom of the cylinder 14 conducts any water which may leak by the piston to the waste pipe 18. Any water which leaks from the chamber above the valve 79 around the hollow stem 79', or through the ducts 82, when closed by spindle 83, will flow into the chamber 85 and passage 85' and finally into the waste pipe.

The spindle 83, valve 79 and valve seat 79² are made of metal which will resist corrosion. The valve seat is formed with indentations 79³ to permit engagement of a special tool for the insertion and removal of the seat. The inlet pipe 12 is provided with a strainer 12' to prevent any solid matter being carried in with the water which operates the power piston.

In the practical application of the apparatus shown in Figs. 1 to 10 it was found that the doors for admitting air into the setting would not at times close until after the temperature of the superheated steam had fallen a considerable amount below that at which the doors were opened. This was due to the use of an unbalanced valve and friction losses. For example, if the doors opened when the superheated steam reached a temperature of 500° F., they would sometimes not close until the temperature had fallen to 475° F. Under most conditions of operation, as an emergency device, this fall in temperature of the superheated steam below that at which the doors were opened, is not objectionable, as the fireman or attendant can readily press down lever 63 after the superheated steam has been reduced to the desired degree and thus bring the apparatus to its initial condition in which it will remain until the temperature of the steam flowing over the coil 2 again reaches the temperature to which the apparatus is set. In order, however, that the doors for admitting air to the setting shall close immediately after the temperature of the steam flowing over the coil 2 falls below that at which the apparatus is set, I have devised the construction illustrated in Fig. 23. In this construction, the valve spindle 64' is connected to the end of lever 63, the valve 64 normally closing the end of the water inlet 88. When the valve is opened the water flows through passage 89 raising ball valve 89', thence into the chamber 90 from which the water is admitted into power cylinder 14. During the time that the valve 64 is open and the piston 15 descending, a portion of the water from chamber 90 flows through the outlet 66 into waste pipe 18, as in the other described constructions. The valve casing is formed with a

vertical channel 91 which communicates with the chamber 92, in which the valve moves, through a duct 93 leading from the lower part of the chamber and controlled by a valve 93'. That portion of channel 91 which is below duct 93 is connected by a pipe 94 with the power cylinder 14, said pipe entering the cylinder at a point which will enable it to be closed by the piston on its downward movement. The lower end of the cylinder is closed by a head 14', and a drain pipe 94' connects the cylinder with the waste pipe 18. The upper end of channel 91, above duct 93, is connected by a duct 95 with a chamber 96 in the valve casing above a piston 97 secured to valve spindle 64'.

When the temperature of the superheated steam flowing over coil 2 reaches that at which the apparatus is set to operate, lever 63 will be raised thereby opening valve 64 to admit water under pressure to the power piston, as before described. When water is admitted to chamber 92 a portion of it flows through duct 93 to the two branches of channel 91. That portion flowing through the lower branch is conducted by pipe 94 to the lower part of cylinder 14 so that during the descent of the cylinder, so long as the outlet of pipe 94 remains open, the water so admitted will escape through the drain connection 94' to waste pipe 18. The water which flows through the upper part of channel 91 is conducted through duct 95 to the chamber 96, above piston 97. There is, however, a comparatively low pressure in the upper part of channel 91 during the time that water flows freely through pipe 94. When piston 15 reaches the end of its downward stroke it covers the opening from pipe 94 thereby stopping the flow of water through said pipe and causing the water to flow through the upper part of channel 91 to chamber 96, the movement of piston 97 not being sufficient to completely close duct 95. When the pressure in chamber 96 becomes great enough to overcome the resistance of valve 64, and if the temperature of the superheated steam flowing over coil 2 is such that there is not too great an unbalanced force tending to maintain the lever 63 in its upper position, the pressure acting on the upper side of piston 97 will close the valve 64. When valve 64 closes, ball valve 89' will close and piston 15 will move upward so as to open the end of pipe 94, and all parts that affect the opening of the valve 64 will be restored to normal position, that is, valve 64 will be automatically closed as soon as the piston 15 reaches the limit of its downward stroke and the piston 15 will return to its original position at the top of the power piston, thus closing the doors in the setting through the levers connected to piston 15 as heretofore described. Valve 64 will remain

closed until the temperature of the superheated steam flowing over coil 2 exceeds the limit for which the apparatus is set. If, therefore, the opening of the doors for admitting air into the setting, or the manipulation of dampers, as before described, causes the temperature of the steam flowing over coil 2 to be reduced the required degree, valve 64 will remain closed and the power piston will return to its normal position thus closing the air admission doors.

Any leakage from chamber 96 around spindle 64' passes into a chamber 98 below piston 97 and thence through the passage 99 to a waste pipe 100. A partition 101 separates chamber 98 from the chamber or water space 92 in which the valve 64 moves. Any leakage through the spindle opening in partition 101 will flow into chamber 98 and thus to waste pipe 100. A strainer 102 in the inlet pipe 88 prevents the entrance of any solid material into cylinder 14.

The form of apparatus shown in Fig. 23 may be employed in a superheat regulating device as well as in a superheat limiting device. When used in connection with a superheat regulating device the amount of superheat would ordinarily be governed by other means than by allowing cold air to flow into the furnace or setting, the means employed being preferably of such a nature as not to lower the efficiency of the apparatus.

What I claim and desire to secure by Letters Patent of the United States is:—

1. A system for the purpose described, comprising a superheater and its setting, an outlet pipe for the superheated steam, a thermostat in said pipe, and means controlled by said thermostat for admitting air into the setting when the temperature of the superheated steam flowing over the thermostat reaches a predetermined degree.

2. A system for the purpose described, comprising a superheater and its setting, an outlet pipe for the superheated steam, a thermostat in said pipe consisting of a container for a volatile liquid, and means controlled by the pressure of the vapor in said container for admitting air into the setting when the temperature of the superheated steam flowing over said container reaches a predetermined degree.

3. A system for the purpose described, comprising a superheater and its setting, doors for admitting air into the setting, an outlet pipe for the superheated steam, a thermostat in said pipe, a cylinder having a piston and connections from the latter to said doors, and means controlled by said thermostat to admit a fluid under pressure to said cylinder to effect the opening of said doors.

4. A system for the purpose described, comprising a superheater and its setting, an

outlet pipe for the superheated steam, a thermostat in said pipe, means controlled by said thermostat for admitting air into the setting when the temperature of the superheated steam flowing over the thermostat reaches a predetermined degree, said means comprising a cylinder and its piston, a pipe for admitting a fluid under pressure to said cylinder, and means for equalizing the pressure on opposite sides of the fluid admission valve.

5. A system for the purpose described, comprising a superheater and its setting, doors for admitting air into the setting, an outlet pipe for the superheated steam, a thermostat in said pipe, a cylinder having a piston and connections from the latter to said doors, a valve controlled pipe through which a fluid under pressure is admitted to said cylinder, means controlled by said thermostat for opening said valve, and means for equalizing the pressure on opposite sides of said valve to restore it to its normal position upon a reduction in the steam temperature to a predetermined degree.

6. A system for the purpose described, comprising a superheater and its setting, an outlet pipe for the superheated steam, a thermostat therein, doors for admitting air into the setting, and mechanism controlled by said thermostat to open the doors when the temperature of the superheated steam reaches a predetermined degree.

7. A system for the purpose described, comprising a superheater and its setting, an outlet pipe for the superheated steam, a thermostat therein, doors for admitting air into the setting, and mechanism controlled by said thermostat to open the doors when the temperature of the superheated steam reaches a predetermined degree, and counterweights to restore the doors to closed position.

8. A system for the purpose described, comprising a superheated steam main, a thermostat within said main, a power cylinder having a valved pipe for admitting fluid under pressure thereto, means for operating the valve in said pipe from said thermostat, said power cylinder having a closed piston and an outlet on the inlet side of the piston and through which a part of the fluid passes when it is admitted into and is under pressure in the cylinder and through which the fluid is exhausted, when the valve is closed, to permit the power piston to return to its normal position.

9. A system for the purpose described, comprising a superheated steam main, a thermostat in said main consisting of a container for a volatile liquid; a regulator having a diaphragm and a connection from said thermostat to one side of the diaphragm, means for balancing the vapor pressure on

said diaphragm, a power cylinder having a valved pipe for admitting fluid under pressure thereinto, means for operating the valve in said pipe by the movements of 5 said diaphragm, said cylinder also having a closed piston and an outlet on the inlet side of the piston and through which a part of the fluid passes when it is admitted into and is under pressure in the cylinder and 10 through which the fluid is exhausted, when the valve is closed, to permit the power piston to return to its normal position.

10. A system for the purpose described, comprising a superheated steam main, a 15 thermostat in said main, a power cylinder having a valved pipe for admitting a fluid under pressure thereinto, means for operat-

ing the valve in said pipe from said thermostat, said cylinder having a closed piston and an outlet on the inlet side of the piston 20 and through which a portion of the fluid is discharged when it is admitted to the cylinder and through which all of the fluid is discharged as the piston returns to its normal position, and means for returning 25 the piston to such position.

In testimony whereof I have hereunto signed my name in the presence of two subscribing witnesses.
